VAPORIZER FOR TWO-STAGE LIQUEFIED
PETROLEUM GAS DISPENSING SYSTEMSLoyd J. White, San Antonio, Tex., assignor to
Southern Steel Company, San Antonio, Tex.,
a corporation of Texas

Application December 28, 1944, Serial No. 570,170

2 Claims. (Cl. 62—1)

1

This invention relates to liquefied petroleum gas dispensing systems, wherein a mixture of liquefied gases, such as butane and propane, is stored in a pressure storage tank and vapor is generated by discharging liquid from the tank through a first-stage pressure reducing regulator into a heat exchanger utilizing the liquid fuel as the heating medium, the generated vapor being delivered from the vaporizer through a second-stage pressure regulator for use in consuming appliances. One of the objects of the invention is to provide a new type of vaporizer, utilizing a segregated portion of the fuel contents of the tank to supply the latent heat of vaporization to the residual liquid which passes through the first-stage regulator. In this respect, the invention involves important improvements in the type of system disclosed in my application Serial No. 237,113, filed October 26, 1938. The main idea is to provide a new type of two-stage pressure reducing, liquid eduction system, wherein liquefied gas in the storage tank is circulated rapidly through a heat exchanger or tank to supply the latent heat of vaporization for the educted liquid. A further and most important aim is to provide an internal vaporizer in the storage tank so constructed and arranged as to provide for complete submergence of the vaporizer in the liquid fuel and thereby insure complete vaporization under normal loads until practically all of the liquid fuel is exhausted from the tank.

Other aims and advantages of the invention will appear in the following description when considered in connection with the accompanying drawing, wherein the figure is a sectional view, partly in elevation, showing a two-stage liquid eduction system embodying the invention.

The improved system is especially contrived to supply liquefied petroleum gas of a uniform B. t. u. content from a mixture of butane and propane. The new vaporizer is shown as being applied to an underground system of the general type disclosed in the aforesaid co-pending application. The fuel usually consists of a mixture composed principally of butane including upwards of twenty per cent propane. If the fuel is vaporized by the batch method, it is subject to weathering and causes trouble, due to variation in the heating value of the gas. This invention, therefore, applies to a two-stage liquid eduction system, wherein the fuel is vaporized between two regulators.

Referring more particularly to the drawing, the invention is applied to an underground system employing a pressure storage tank 10, which

2

is buried in heat exchange relation with the surrounding earth. It is shown as being provided with a single riser or stand-pipe 11 to which is connected a composite valved fitting 12, through which the tank is adapted to be filled. 5 Such a fitting is generally disclosed in my Patent No. 2,176,829, and needs no further description. The stand-pipe and the fitting are arranged within a protecting casing or housing 13 extending above the ground level, so that the fitting is 10 easily accessible from above the ground.

The tank is shown as being partially filled with liquefied petroleum gas which is maintained under pressure, the vapor pressure being dependent upon the temperature and the particular mixture 15 employed, ranging between, say, twenty pounds to fifty pounds per square inch, gauge. In this example, a heat exchanging tank 14, which may be made of relatively thin sheet metal, is shown 20 as being arranged within the tank 10 in the vapor space, so that it is not exposed to heat exchange with the liquid in the main tank. It may be secured to the top portion of the storage tank by welding, as shown, or by any other convenient securing means. Spaced depending 25 pipes 15 and 16 are shown as being connected to the bottom portion of the tank 14 and extending to a point near the bottom of the storage tank, so that liquid fuel may be withdrawn from 30 the storage tank and circulated through the heat exchanger, as will presently be explained. An outlet tube or conduit 17 is shown as being connected to communicate with the top portion of the tank 14 so that liquid or gas, as the case may 35 be, will be withdrawn. The liquid then passes through a first-stage, pressure reducing regulator 18 of the usual type, which reduces the pressure from, say, about forty pounds down to five or ten pounds per square inch. The liquid is 40 partially vaporized, due to its contained heat, as it passes through this first-stage, pressure reducing regulator and the mixture of vapor and residual liquid is delivered through a tube 19 and a heat exchanger or vaporizing coil 20 within the 45 heat exchanging tank 14; thence, through an outlet tube 21, through the valve fitting 12 and an ordinary second-stage regulator 22 connected thereto, which reduces the pressure to the desired 50 service pressure of about six ounces. The gas and is delivered to the consuming appliances.

It will be noted that the heat exchanging tank or compartment 14 is relatively small in comparison with the capacity of the main tank 10. The arrangement is such that, when gas is being con-

sumed, the vapor pressure within the heat ex-changing tank is reduced, thereby permitting liquid to rush into the vaporizing tank, due to the superior vapor pressure existing in the storage tank. The vaporizing tank is promptly filled with liquid because only a slight pressure reduction will be sufficient to cause the liquid to rise in the two pipes 15 and 16. It will be understood that mixtures of butane and propane have a specific gravity of five tenths or less, depending upon the amount of propane in the mixture and, since storage tanks are usually not more than two or three feet in diameter, pressure reduction of only a few ounces will be sufficient to cause the liquid to rush into the heat exchanging tank and keep it full.

The liquefied fuel, which fills the heat ex-changing tank, supplies the sensible heat or latent heat of vaporization for the residual liquid discharged through the first-stage, pressure reducing regulator 18. The arrangement of the coil 20 is such that its coldest portion or intake end is above the depending tube or pipe 16 and the outlet end, which is the warmest portion, is above the depending tube or pipe 15. Due to this arrangement, the liquid is thermo-syphonically circulated very rapidly through the heat exchanging tank, the coldest liquid naturally settling or circulating downwardly very rapidly as it is chilled. The greater the demand for fuel, the greater will be the rate of circulation of the liquid in heat ex-changing contact with the coil 20. Furthermore, the arrangement is such that the coil will be completely submerged in the liquid fuel, thereby insuring complete vaporization thereof, as long as there is any fuel in the storage tank. This over-comes one of the great difficulties encountered in connection with systems employing coils or vaporizing chambers submerged in the body of liquid within the tank. When they are exposed to heat exchanging contact with the vapor in the tank, the rate of heat transfer is considerably diminished and is some times insufficient to insure vaporization of the residual liquid between the pressure reducing regulators, especially, when the demand reaches a maximum.

In the operation of the system, the heat ex-changing tank will be filled with gas at the same vapor pressure as that in the storage tank when no gas is being consumed. In other words, the liquid levels in the two tanks will be equalized. However, as soon as there is a gas demand by the consuming appliances, such as cook stoves, water heaters and the like, the supply of trapped gas in the heat exchanging tank or chamber will quickly be exhausted and replaced by liquid fuel, due to the reduction in vapor pressure. The liquid fuel will fill the heat exchanging tank and keep it liquid full as long as there is any sub-stantial demand for gas by the consuming appli-ances, thus insuring complete vaporization of the residual liquid in the heat exchanging coil.

From the foregoing description, it will be un-derstood that this invention provides a very sim-

ple and efficient vaporizer for two-stage liquid eduction systems which insures uniform heat ex-changing contact with the heat exchanging coil as long as there is any fuel available in the system. Moreover, the heat exchanger can easily be in-stalled in a tank and it can be made of very thin sheet metal, because the pressure difference be-tween the vapor or liquid in the small tank and the main tank will be quite small.

Obviously, the present invention is not limited to the particular embodiment thereof herein shown and described.

What is claimed is:

1. In a liquefied petroleum gas dispensing sys-tem of the character described, an underground pressure storage tank adapted to be charged with a mixture of liquefied gases; a heat exchanging chamber, in the form of a small tank arranged in the vapor space of said storage tank; a pair of spaced depending pipes connected to the cham-ber and communicating with the bottom portion of the storage tank; an eduction pipe connected to the upper portion of the chamber and carry-ing a first-stage pressure reducing regulator; a vaporizing coil within the chamber connected to the eduction pipe to receive the educted fuel passing through said regulator; eduction pipe extending through the upper portion of said stor-age tank at spaced points, and serving to hold said small tank in place; a vapor outlet conduit connected to the coil; and a second-stage pres-sure reducing regulator connected to said vapor delivering conduit.

2. In a liquefied petroleum gas dispensing sys-tem of the character described, a pressure storage tank adapted to be buried underground and to be charged with a mixture of liquefied gases; a cylindrical heat exchanging chamber suspended within the gas space in said tank; spaced, de-pending pipes connected to said chamber and communicating with the bottom portion of said tank; an eduction tube connected to the upper portion of said chamber and extending outside of said tank; a first-stage, pressure reducing reg-ulator connected to said eduction tube; said eduction tube extending through the upper portion of the tank at spaced points to hold the chamber in place; a vaporizing coil within the chamber and connected to receive educted fuel from said regulator; a vapor delivering conduit leading from said coil to the point of use; and a second-stage pressure reducing regulator connected to said vapor delivering conduit.
